(57) **CLAIM**

The ornamental design for a surface mount electronic cam lock, substantially as shown and described.

DESCRIPTION

FIG. 1 is a front left perspective view of a first embodiment of a surface mount electronic cam lock according to our new design;

FIG. 2 is a top plan view thereof;

FIG. 3 is a left side view thereof;

FIG. 4 is a front elevation view thereof;

FIG. 5 is a right side view thereof;

FIG. 6 is a bottom plan view thereof;

FIG. 7 is a front left perspective view of a second embodiment of a surface mount electronic cam lock according to our new design;

FIG. 8 is a top plan view thereof;

FIG. 9 is a left side view thereof;

FIG. 10 is a front elevation view thereof;

FIG. 11 is a right side view thereof; and,

FIG. 12 is a bottom plan view thereof.

Features shown in dashed lines are not part of the claimed design, nor is the rear side.
